No. 897,676.

PATENTED SEPT. 1, 1908.

G. THOMPSON.

FLUID FEEDING PRESSURE MECHANISM.

APPLICATION FILED JULY 24, 1907.

UNITED STATES PATENT OFFICE.

GEORGE THOMPSON, OF MANSFIELD, OHIO, ASSIGNOR OF ONE-HALF TO FRANK SCHREIDT,
OF MANSFIELD, OHIO.

FLUID-FEEDING-PRESSURE MECHANISM.

No. 897,676.

Specification of Letters Patent.

Patented Sept. 1, 1908.

Application filed July 24, 1907. Serial No. 385,373.

To all whom it may concern:

Be it known that I, GEORGE THOMPSON, citizen of the United States, residing at Mansfield, in the county of Richland and State of Ohio, have invented certain new and useful Improvements in Fluid - Feeding - Pressure Mechanism, of which the following is a specification.

My invention relates to improvements in a fluid feeding pressure mechanism for operating the carriage of machine tools and other similar devices.

It is well known to those skilled in the operation of machine tools, that in order to produce the most efficient result in the least possible time it is necessary for the feed of the machine to be rigid and regular and under perfect control of the operator. This result has heretofore been more or less satisfactorily attained by the use of various mechanical means which operate with more or less efficiency.

Therefore the objects of my invention are: 1st. To construct a feed mechanism for machine tools or any other device which shall operate by fluid pressure thereby dispensing with the mechanical means heretofore used.

Another object of my invention is the construction of a device of the class described which shall transmit a rigid and uniform and variable motion to the carriage to which it is attached.

A further object is the construction of a feed mechanism in combination with a governing device which shall enable the operator to instantly control the speed of the feed.

A further object is the construction of a feed mechanism that may be easily attached to any machine desired.

I attain these and other objects by the mechanism illustrated in the accompanying drawings in which:

Figure 1 is a longitudinal side elevation of my device attached to a milling machine and operated by compressed air. Fig. 2 is a side elevation of the four-way valve I use to control the air supply. Fig. 3 is a cross section of Fig. 2, showing the ports in full and dotted lines. Fig. 4, is a sectional side elevation of a modification of the auxiliary cylinder showing counter-bore.

In the drawings, reference numeral 1 indicates a bracket rigidly secured to a milling

machine 2 by bolts 3. A power cylinder 4, made integral with the free end of the bracket 55 1, is provided with suitable heads 5 and 6 fitted to and rigidly secured to opposite ends of the cylinder 4 by bolts 7 passing through suitable openings in the heads 5 and 6 and adapted to engage with the internal screw-threaded 60 apertures formed in the flanges 8 and 9 made integral with the cylinder 4. An auxiliary cylinder 10 is fitted with suitable heads 11 and 12 provided with exterior screw threads adapted to engage with the internal screw threads 65 formed in the ends of the auxiliary cylinder. A cupped boss 13, made integral with the head 11, is provided with internal screw-threads adapted to engage with the exterior screw-threads formed on the cupped boss 14 made 70 integral with the head 6 and thereby rigidly securing the cylinder 10 to cylinder 4 in concentric alinement therewith. The above structure is the preferable construction. A piston rod 15 is fitted to suitable openings 75 16 in the heads 5 and 6 of cylinder 4 having one end 17 projecting therefrom and fitted with screw-threads adapted to engage with a threaded opening formed in the end of the carriage 18 of the milling machine 2 or any 80 other device that is provided with a feeding device and is rigidly secured therein by a lock nut 19 fitted to the piston rod and adapted to contact with the end of the carriage. The opposite end 20 of the piston rod 15 projects 85 through a suitable aperture 21 formed in the head 11 of cylinder 10 and is fitted with a piston 22 having internal screw-threads formed in the aperture 23 adapted to engage with the external screw-threads formed on 90 the reduced portion 24 of the piston rod 15. The piston 22 is fitted to and adapted to reciprocate in cylinder 10 and is for a purpose hereinafter specified. A piston 25 having an internal screw-threaded aperture 26, adapted 95 to engage with the external screw-threads formed on the enlarged portion 27 of the piston rod 15 is loosely fitted to and adapted to reciprocate in cylinder 4. Cupped packing washers 28 are fitted to opposite ends of the piston 24 and are held there-against by nuts 29 fitted to the threaded portion 27 of the piston rod. The washers 28 are fitted to the cylinder 4 and are adapted to prevent leakage of air by the said piston. The stuffing 100 box 30 made integral with the cylinder head

5, is fitted with a suitable gland 31 and cap 32. A recess 33 is formed in the said stuffing box concentric with the piston rod 15 and is adapted to receive packing to prevent the 5 escape of air from the cylinder. The recess 34 formed in the boss 14 and surrounding the piston rod 15 is adapted to receive suitable packing to prevent the escape of the contents of the cylinders 4 and 10.

10 While any suitable valve may be used to control the supply of fluid, I prefer to use a four-way valve as shown in the drawings. This controlling valve 35 may be placed in convenient reach of the operator and preferably connected with an air or steam supply pipe 36. Suitable pipes 37 and 38, having one end connected to the four-way valve and the opposite ends to ports 39 and 40 formed in the walls of the cylinder 4, form a connecting passage between the air or steam supply and the power cylinder.

Referring to Fig. 3, the supply pipe 36 is connected with the port 41 and the lead pipes 37 and 38 are connected with ports 42 and 43 respectively. An exhaust pipe 44 is connected with a port 45 and leads to the atmosphere. A valve plug 46 is fitted to the valve case 46^a and is adapted to be rotated therein by means of the lever 47. See Fig. 1.

30 Suitable ports 48 and 49 are formed in the valve plug 46 and form a means of communication between the ports 41 and 43, and 42 and 45 respectively; or when the valve is rotated one-fourth revolution, they will form a 35 means of communication between ports 42 and 41, and 43 and 45 respectively as shown by full and dotted lines in Fig. 3.

Opposite ends of the cylinder 10 have suitable apertures 50 and 51 communicating 40 with the interior thereof and are adapted to receive opposite ends of the pipe line 52 thereby forming a by-pass. A suitable valve 53 is included in the said pipe line and forms a means of regulating the size of the by-pass. 45 By removing the plugs 54, the cylinder 10 and by-pass 52 may be filled with oil or other suitable liquid which forms the means of governing the reciprocation of the pistons and rod 15.

50 The operation of my device is as follows: By referring to Figs. 1 and 3, it will be observed that when the controlling lever 47 is in the position shown by the full lines, (see Fig. 1), the port 48 will connect the ports 41 and 42 and allow the air or steam to pass from the supply pipe 36 through the lead pipe 37 and port 39 into the end D of cylinder 4 thereby forcing the piston 25 in the direction of the arrow. When the controlling 55 lever 47 is in the position indicated by the dotted lines, the ports 48 and 49 are in the position shown by the full lines in Fig. 3, thus allowing the air or steam to pass from the supply pipe 36 through the lead pipe 38 and port

40 into the end E of cylinder 4 and thereby 65 forcing the piston 25 to return to the end D of cylinder 4. The air or steam in the end D of cylinder 4 is allowed to escape to the atmosphere through the port 39 and lead pipe 37 into port 48 and exhaust pipe 44. The 70 air or steam in the end E is exhausted in a similar manner through the port 40 and lead pipe 38 into port 49 and exhaust pipe 44. The reciprocating motion of the piston 25 is imparted to the carriage 18 by means of the 75 piston rod 15.

It will be noted that when the piston 25 is moved in the direction of the arrow, the hereinbefore mentioned piston 22 is forced in the same direction by means of the piston 80 rod 15. The said piston 22 is adapted to closely fit the bore of cylinder 10 thereby forcing the liquid in cylinder 10 through the by-pass 52 from front to rear of the said piston. By opening or closing the valve 53, a 85 large or small volume of the liquid in cylinder 10 will be allowed to pass through the said valve, thus regulating the speed of the pistons as desired in proportion to the opening. If it is desired to have the pistons move 90 slowly in one direction and fast in the opposite, an orifice 55 may be provided in the piston 23, as shown. A check valve 56, fitted to the piston 22, is adapted to close the said orifice when the pistons move in one direction and open when the said pistons have a reverse movement, thereby allowing the liquid to return to the opposite end of the cylinder at a more rapid rate.

In Fig. 4 I have shown a counter-bore 57 100 formed on the inner periphery of the auxiliary cylinder for the purpose of increasing the speed of the return stroke of the piston after the cutter leaves the work thereby expediting the operation of the feeding mechanism. The increased speed is derived from the larger bore represented by the counter-bore 57 which allows an increased flow of fluid past the piston. It is obvious that the cylinder can be counter-bored at any point 105 and for any length desired.

Having fully described my invention, what I claim and desire to secure by Letters Patent, is:

1. In a fluid pressure feeding mechanism 115 comprising a power cylinder having a piston fitted to reciprocate therein through the medium of an elastic fluid, a governing cylinder arranged in tandem with said power cylinder having the bore thereof filled with fluid, a 120 piston fitted to reciprocate therein, a piston rod connecting the pistons in the power cylinder and governing cylinders having one end projecting through the head of the power cylinder, a carriage or the like for feeding purposes connected to said piston rod, substantially as, and for the purpose described.

2. In a fluid pressure feeding mechanism

comprising a power cylinder, a piston fitted to reciprocate therein, means to permit the inflow of air on both sides of said piston and to exhaust it therefrom, cupped washers fitted to each side of said piston and adapted to prevent the flow of fluid past said piston, a governing cylinder connected in tandem with said power cylinder, a piston fitted thereto, said governing cylinder being filled with oil, 10 a by-pass to permit communication with the front or rear end of the governing cylinder, a piston rod secured to the pistons in the power and governing cylinders leaving one end projecting from the power cylinder, a feeding table connected to one end of said piston rod, said power cylinder having ports formed in each end thereof, a supply pipe, a three-way valve connected to said pipe, means to connect said three-way valve to each end of said 20 power cylinder whereby fluid under pressure can enter either end of the cylinder and be exhausted therefrom.

3. In a fluid pressure feeding mechanism, the combination of power and governing cylinders arranged in tandem with each other and connected together, pistons fitted to reciprocate in said cylinders, a piston rod connecting both of said pistons with one end projecting from the power cylinder, and a feeding table or the like connected to the piston rod, said governing cylinder containing a fluid, a by-pass connecting each end of said governing cylinder, means on the by-pass to retard or permit the free passage of the fluid from either end of the governing cylinder for governing purposes.

4. In a fluid pressure feeding mechanism comprising a main power cylinder and an auxiliary governing cylinder, said governing cylinder being filled with oil, pistons fitted to reciprocate in said cylinders, a piston rod to connect said pistons to provide for simultaneous reciprocation, a carriage connected to one end of the piston rod, ports provided in the power cylinder, a supply pipe, a three-way valve attached to said pipe, means to connect said three-way valve to both ends of the power cylinder whereby the fluid under pressure can flow into either end of the power cylinder or be exhausted therefrom, substantially as and for the purpose described.

5. In a feeding mechanism for milling machines or the like comprising a power cylinder, a piston fitted to reciprocate therein, a governing cylinder of smaller diameter arranged in tandem with and connected to said power cylinder, a piston fitted to reciprocate in said governing cylinder having an aperture formed therein, a piston rod to connect both pistons, a carriage connected to one end of the piston rod, a valve to close said aperture on one side when the piston in the governing cylinder is moving in one direction whereby a quicker return movement can be

obtained of the carriage, a by-pass connecting each end of the governing cylinder to permit the passage of fluid from either end of the cylinder, means on said by-pass to retard the flow of said fluid therethrough to regulate the speed of the carriage, as and for the purpose described.

6. In a pressure feeding mechanism, a main power cylinder, a piston fitted thereto, cup-shaped washers secured to said piston, an auxiliary governing cylinder connected to one end of said power cylinder, a piston fitted to reciprocate therein, a piston rod connecting the piston in the power cylinder and the piston in the regulating cylinder, a feeding table connected to said piston rod, said power cylinder having ports formed in the lower portion thereof adjacent to each end, a supply pipe, a three-way valve connected thereto, means to connect said three-way valve to both ends of said power cylinder to permit or prevent the flow of fluid under pressure to either end of said cylinder, and exhaust it therefrom, substantially as described and for the purpose set forth.

7. In a feeding mechanism for moving the table of a machine or the like, cylinders of different diameters arranged in tandem with each other and connected together, pistons fitted to said cylinders, a piston rod to carry said pistons, a table for feeding purposes connected to said piston rod, one of said cylinders adapted to receive fluid under pressure through ports formed in each end thereof and the other cylinder having its bore filled with oil to govern the reciprocation of the table, a by-pass connecting both ends of said bore whereby the fluid contained in the governing cylinder can pass from either end of the cylinder when movement is imparted to the piston, means to obstruct the passage of the oil more or less therethrough.

8. In a feeding mechanism adapted to be attached to a movable table or the like, a bracket, a power cylinder mounted on said bracket having ports formed in each end thereof, a piston fitted to reciprocate therein, said table being attached to one end of the piston for feeding purposes, cup-shaped washers secured to said piston, an auxiliary cylinder, a piston fitted thereto, a piston rod to connect both pistons, a supply pipe, a three-way valve secured to said supply pipe, means to connect the ports of each end of the power cylinder to each side of the three-way valve whereby the fluid under pressure can be permitted to flow into either end of the power cylinder or be exhausted therefrom, said auxiliary governing cylinder provided with screw-threaded orifices on each end, a by-pass connecting said orifices, means to obstruct the passage way of said by-pass when the fluid is passing from one end of the auxiliary cylinder to the opposite end.

4

9. In a fluid pressure feeding device comprising a power cylinder, a piston fitted to reciprocate therein, an auxiliary governing cylinder filled with oil, a piston fitted to reciprocate therein, a piston rod connected to both pistons whereby both pistons move simultaneously when movement is imparted thereto, a carriage connected to one end of the piston rod, said auxiliary cylinder govern-

ing the movement of the carriage in both directions as described and set forth.

In testimony whereof I affix my signature in presence of two witnesses.

GEORGE THOMPSON.
